UNITED STATES PATENT OFFICE.

HERBERT J. HOGAN, OF LOS ANGELES, CALIFORNIA.

AEROPLANE.

1,272,805.

Specification of Letters Patent. Patented July 16, 1918.

Application filed June 25, 1917. Serial No. 176,846.

To all whom it may concern:

Be it known that I, HERBERT J. HOGAN, a citizen of the United States, residing at Los Angeles, in the county of Los Angeles 5 and State of California, have invented a new and useful Aeroplane, of which the following is a specification.

My invention relates to the art of aviation, and more particularly to the heavier than 10 air machines which are commonly termed aeroplanes.

The principal object of my invention is to provide a special form of control for use in such planes.

15 A further object of my invention is to provide means for shifting the weight of the operator to compensate for changes in the control. More specifically my invention provides for changing the angle of the planes 20 with relation to the body of the plane.

Further objects and advantages will be made evident hereinafter.

Referring to the drawings, which are for 25 illustrative purposes only:

Figure 1 is a side elevation of an aeroplane equipped with my invention, a portion of the body being broken away to better illustrate the invention.

Fig. 2 represents a section on a plane represented by the line 2—2 of Fig. 1.

Fig. 3 is a plan view, partly in section, showing the method of control.

In the form of the invention illustrated in these drawings, an aeroplane body 11 is 35 shown. This body is provided with a propeller 12 at the forward end. It is driven by a suitable engine not shown. Suitable guiding and controlling means 13 are provided at the rear of the body 11, and ailerons 40 or suitable stabilizing means may be supplied, in accordance with standard practice.

The engine, and method of controlling the engine, and the method of controlling the means 13, and the ailerons, are omitted from 45 the drawings, as they form no portion of the present invention, being well known in the art.

My invention is shown as applied to a biplane. It may, however, be applied to a 50 monoplane, or indeed to machines having any number of planes, by means of suitable modifications, which can be accomplished without the necessity of invention.

In the form shown, a pair of upper side 55 planes 15 are used in combination with an upper central plane 16. The planes 15 and

16 are pivoted on a shaft 17 carried on the upper end of a strut 18, and lower side planes 19 are pivoted on a shaft 20, which is secured in the side of the body 11 and 60 which passes through the lower end of the strut 18. The shafts 17 and 20 are at or a little in front of the centers of pressures of the wings in their normal position. Pivoted onto the planes 15 and 16, by means of a 65 shaft, are connecting bars 21. The bars 21 are pivoted to the planes 19 by means of shafts 23. The shafts 23 pass through the sides of the body 11, and are engaged by the extreme end of levers 24 which are secured 70 to the shaft 20. Secured on the shaft 20 is a hand lever 25 which is provided with a pawl 26 which engages a toothed segment 27. The pawl 26 is operated by an auxiliary handle 28. Rigidly secured to the shaft 75 20, is a seat lever 30, which is connected to the bottom of a sliding seat 31 through a link 32. The seat 31 is mounted on the ways 33 secured to the inside of the body 11.

The method of operation is as follows: 80

The planes 15, 16 and 19 may be considered as normally in the position shown in full lines in Fig. 1. Whenever the operator desires to change the inclination of the planes with relation to the body 11, he 85 moves the hand lever 25 backward or forward, first releasing the pawl 26 by means of the auxiliary handle 28. By suitable manipulation of the handle 25 he can adjust the planes with relation to the body 11, 90 throwing them into the position shown in dotted lines in Fig. 1, or into any intermediate position. As the lever 25 is moved backward or forward the seat 31 is also shifted 95 backward or forward, thus varying the distribution of the weight of the aviator on occupying the seat. This change in the distribution of the weight compensates for the change in position.

I claim as my invention:— 100

1. An aeroplane comprising a body; propelling and guiding means for said body; a pair of struts secured to said body; an upper pivot secured at the upper end of each of said struts; a lower pivot secured to the 105 lower end of each of said struts; upper planes pivoted on said upper pivots; lower planes pivoted on said lower pivots; connecting bars connecting said upper and lower planes; a lever system for raising and lowering said connecting bars; a sliding seat on which the aviator may sit; means for oper- 110

ating said sliding seat from said lever system; and means for locking said lever system in any one of several positions.

2. An aeroplane comprising a body; propelling and guiding means for said body; a pair of struts secured to said body; an upper pivot secured at the upper end of each of said struts; a lower pivot secured to the lower end of each of said struts; upper planes pivoted on said upper pivots; lower planes pivoted on said lower pivots; connecting bars connecting said upper and lower planes; operating levers rigidly secured to said lower pivot and connected at their outer ends to said connecting bars; a hand lever fixed to said lower pivot; a seat slidably mounted in said body; means for so connecting said seat to said lower pivot that said seat is moved forward or back as said hand lever is moved; and means for locking said hand lever at various positions.

3. An aeroplane comprising a body; propelling and guiding means for said body; a pair of struts secured to said body; an upper

pivot secured at the upper end of each of said struts; a lower pivot secured to the lower end of each of said struts; upper planes pivoted on said upper pivots; lower planes pivoted on said lower pivots; connecting bars connecting said upper and lower planes; operating levers rigidly secured to said lower pivot and connected at their outer ends to said connecting bars; a hand lever fixed to said lower pivot; a seat slidably mounted in said body; means for so connecting said seat to said lower pivot that said seat is moved forward or back as said hand lever is moved; and means for locking said hand lever at various positions.

In testimony whereof I have hereunto set my hand at Los Angeles, California, this 16th day of June, 1917.

HERBERT J. HOGAN.
